CABLE SUPPORT

Herbert E. Miller, Washington, D. C., assignor to
 Electrical Manufacturing Company, Battle
 Creek, Mich., a corporation of Michigan

Application June 24, 1940, Serial No. 342,176

10 Claims. (Cl. 248—73)

The following description relates to an invention in cable supports of the type customarily used for electrical cables. These supports are ordinarily installed in the manhole compartments of underground conduits. In such circumstances it is an important consideration to provide equipment easy to install and capable of caring for an increase in the number of the cables that might be required later.

It is also an object of my invention to provide a cable support which will combine strength with a minimum of weight of metal.

A further object of my invention is to simplify the operations by which the several parts of the device are fabricated, reduce the number of parts and make them interchangeable with existing equipment.

Among the objects of my invention is to insure the satisfactory normal position of the parts without danger of accidental disengagement or removal.

Incidental to my invention I have provided novel means for holding the arms to the bracket in the desired position.

Other objects of my invention will be evident from the following description showing the preferred form of my invention and in which

Fig. 1 is a side elevation of my improved cable support;

Fig. 2 is a front elevation of the bracket;

Fig. 3 is a top plan view of the arm;

Fig. 3^a is a fragmentary plan view of the arm with insulators mounted;

Fig. 4 is a bottom view of the arm;

Fig. 5 is a fragmentary plan view of a modified form of the arm;

Fig. 6 is a plan view of the sheet metal blank in the process of fabrication;

Fig. 7 is a side view partly in section on the line 7—7 of Fig. 8 showing a modified form of fastening and

Fig. 8 is a plan view of the same partly in section on the line 8—8 of Fig. 7.

Broadly speaking, the improvement consists in redesign both of the supporting bracket and the arms held by it so that a minimum amount of material will be used and ease of assembly and stability will be effected. By the arrangement described hereinafter, I have found it possible to design an arm which will be supported rigidly on a bracket in a definite position at right angles thereto and braced with respect to the bracket at points above and below the arm. This avoids the necessity of relying for support upon the base or back of the bracket itself. In this way the

position of the arm can be established without the necessity of providing accurate dimensions and spacing for the several parts of the bracket.

The invention is an improvement over that disclosed in my earlier patent granted November 3, 1931 No. 1,830,438 to which reference, however, may be made for the broad features of devices of this type.

My preferred support consists in general of a bracket, one or more cross-arms and suitable holders of insulating material by which the one or more cables are supported on the several cross-arms.

In the drawings I have shown the bracket 11. This is constructed preferably of pressed steel and has a back or base portion 12. At each end the portion 12 is offset as at 13, 13 to provide attaching ends 14 and 15. In general it will be desired to have the base portion forwardly of the ends 14 and 15 but conditions of use may suggest the reverse arrangement to economize space. Holes 16 and 17 are provided in the ends 14 and 15 respectively for the use of attaching bolts or the like. Extending substantially for the full length of the base 12 exclusive of the ends 14 and 15 and along one edge of the base there is a flange or web 18 as shown in Figs. 1 and 2. This flange is integral with the base 12 and together with it provides an L-shaped angle iron.

Near the top of the flange 18 it is cut away to form the opening 19 having an enlarged inner recess 20. A tongue 21 extends partly across the opening 19 and narrows the latter. This tongue has a transverse perforation or opening 22 by which fastening means are applied. In the example illustrated three such openings 19 are provided although the number may be increased or diminished in accordance with the particular needs. The openings 19 are spaced apart sufficiently to permit each to receive a cross-arm with the appropriate spacing for the insulator carried by the arm.

An arm 23 is mounted in position upon the flange 18 oppositely one of the openings 19. This arm 23 is formed from the blank 24 illustrated in Fig. 6. This blank provides the bottom 25 and two side walls 26 and 27 which are bent upwardly to form an open upwardly extended channel. The bottom 25 at one end is slotted longitudinally as at 28. The slot has a width sufficient slidably to receive the flange 18 around which it straddles in the final mounted position.

The side edges of the blank are bent laterally to form the flanges 29 and 30. These flanges are punched to provide openings 31 to receive hold-

ing straps for the insulators. On the flanges 29 and 30 the material is slit for a short distance inwardly from one end to form tongues 32, 32. In the course of fabrication the tongue portions adjacent the slits 32 are bent inwardly and upwardly to form the stop 33 and preferably welded together.

The inner ends of the flanges 29 and 30 are also slit inward and the portions 34, 34 thus formed are cut away to form tongues with spaced extensions 35 which meet when the tongues are bent inwardly. These extensions may then be attached together as by welding 36. This provides a bridge 37 with a central opening. The extensions 35 are spaced from the end of the arm as shown in Fig. 3 to allow for the flange 18. Optionally the inner extensions 35 may be omitted.

The bottom 25 at the inner end of the slot 28 is offset to form a depressed foot 33 (Fig. 1).

The operations on the blank 24 above indicated may be carried out in any convenient order and by any usual means.

Instead of the integral bridge 37, a bridge plate 39 may be provided. This plate has a central opening which overlies the inner portion of the slot 28. The bridge plate 39 in this position between the flanges 29 and 30 is held fixedly by any suitable means. In Fig. 5 I have shown this bridge plate to be attached between the side walls of the channel by means of spot-welding 39'.

Referring particularly to Figs. 7 and 8 it will be noted that this bridge plate may take the form of that shown at 40 in which it is slightly narrower than the space between the side walls 26 and 27. One end has lateral extensions 41 and these have offsets 42, 42. In this way the bridge member 38 may be assembled during fabrication between the walls 26 and 27 with the extensions 41 projecting outwardly through opening 43 in the latter. The bridge member is free to adjust itself longitudinally but the weight of the arm exerted as a turning moment around the foot 33 will cause the extensions 41 to rest against the ends of the opening 43 with the offset portions fitting on the outer surfaces of the sides 26 and 27 and consequently spacing the channel arm with respect to the tongue 21 and the flange 18.

The arm 23 is readily inserted in position by passing the bridge 37 or 40 through the opening 19 and allowing the front portion to drop within the enlarged recess 29. This brings the tongue 21 up through the central opening. The bridge may be held down by applying a cross-pin 44 through the opening 22.

The bottom 25 of the channel arm then straddles the flange 18 which is in the slot 28. In some instances but not always, the depressed foot 34 may be provided to insure support of the arm at this point. The turning moment will tend to keep the bridge resting against the inner edge of tongue 21 and the bottom of the arm against the front edge of the flange 18. In this position the arm 23 is definitely located without reliance upon its support from any other part such for example as the base 12.

The arm 23 thus provides an open upward channel as shown in Fig. 3. In this channel appropriate cable supports such as insulators 45 may be mounted. I have shown the insulators 45 to be made of identical interengaging or complementary portions 46 and 47. These provide a central passage 48 in which the cable rests. The outer side walls of the insulators are grooved as shown in 49 to receive a sheet metal strap 50. The ends of the strap are brought down and

bolted as at 51 through the openings 31 in the flanges 29 and 30. Thus as shown in Fig. 3a the straps and insulators form a substantially complete covering for the channel in the arm. It will be evident that the improved arm above described is equally useful for supporting the customary insulating saddles having longitudinal ribs such as are illustrated in my prior patent granted November 3, 1931 No. 1,830,438.

The assembly of this support will be self-evident. The bracket is bolted to the side wall of the underground compartment or other support. One or more arms 23 are mounted as above described and locked into place by means of pins 44. The insulator sections 46, 47 are built up around the cable and fastened down by means of the straps. Sufficient spacing is provided vertically between arms 23 to accommodate the cables as desired. Therefore, arms can be supplied or removed as occasion demands.

It will be noted that this cable support utilizes a minimum weight of metal and number of parts, can be fabricated simply and readily put in service to suit normal conditions in widely varying applications.

While I have described the preferred form for purposes of illustration, the invention may be embodied in other forms with changes in material and proportions limited only by the scope of the appended claims.

What I claim is:

1. A cable support having a bracket with an outwardly extending flange, said flange having an opening inwardly from its free edge, a tongue extending partly across said opening, an arm having an upwardly directed channel, a perforated bridge across one end of the channel, the channel being slotted below the bridge so that the arm will straddle the flange when the bridge rests in the opening and surrounds the tongue.

2. A cable support having a bracket with an outwardly extending flange, said flange having an opening inwardly from its free edge, a tongue extending partly across said opening, an arm having an upwardly directed channel, a perforated bridge across one end of the channel, the channel being slotted below the bridge so that the arm will straddle the flange when the bridge rests in the opening and surrounds the tongue, an insulator seated on the arm over the channel and a strap around the insulator and having its ends covering the channel.

3. A cable support having a bracket with an outwardly extending flange, said flange having an opening inwardly from its free edge, a tongue extending partly across said openings, an arm having an upwardly directed channel, a perforated bridge across one end of the channel, the channel being slotted below the bridge so that the arm will straddle the flange when the bridge rests in the opening and surrounds the tongue and a depressed foot on the arm adjacent the slot.

4. A cable support having a bracket with an outwardly extending flange, said flange having an opening inwardly from its free edge, a tongue extending partly across said opening, an arm having an upwardly directed channel, a perforated bridge across one end of the channel, the channel being slotted below the bridge so that the arm will straddle the flange when the bridge rests in the opening and surrounds the tongue and fastening means on the tongue for holding the bridge against dislodgment.

5. A cable support having a bracket with a

base and a flange extending at a right angle from one side edge of the base, an opening running inwardly from the free edge of the flange, a perforated tongue extending partly across said opening, an arm having an upwardly directed channel and lateral flanges, a slotted bridge between said flanges at one end of the arm, the arm having a longitudinal slot in the base of the channel below the bridge, a depressed foot at the end of the said slot, an inwardly extending stop at the opposite end of the channel, an insulator seated on the arm over said channel and a strap around the insulator and attached to said flanges.

6. An arm for a cable support having a longitudinal channel and lateral flanges, a slotted bridge between said flanges at one end of the arm, a longitudinal slot in the base of the channel below the bridge and a depressed foot at the end of the said slot. 15

7. An arm for a cable support having a longitudinal channel and lateral flanges, a slotted bridge between said flanges at one end of the

arm, a longitudinal slot in the base of the channel below the bridge, and means to hold the bridge between the flanges.

8. An arm for a cable support having a longitudinal channel and lateral flanges, a slotted bridge, extensions on the sides of the bridge, and openings in the side walls of the channel to receive the extensions of the bridge.

9. An arm for a cable support having a longitudinal channel and lateral flanges, a slotted bridge, extensions on the sides of the bridge, offset portions on said extensions and openings in the side walls of the channel to receive the extensions of the bridge with the offset portions in contact with the sides of the arm. 10

10. An arm for a cable support having a longitudinal channel and lateral flanges, an end portion of each flange being separate from the remainder of the flanges and bent inwardly and spaced projections on the edges of said end portions engaging over said channel. 20
